United States Patent

Des. 238,067

Patented Dec. 16, 1975

238,067

PANEL FOR A DOOR

Frederick V. Caropresi, Pittsburgh, Pa., assignor to
Pease Company, Fairfield, Ohio

Filed Dec. 11, 1972, Ser. No. 314,258

Term of patent 14 years

Int. Cl. D25—01

U.S. Cl. D13—1 J

FIG-1

FIG-2

FIG-3

FIG. 1 is a front elevational view of a door panel of my design;

FIG. 2 is a perspective view of the door panel; and

FIG. 3 is a fragmentary section of the panel taken as indicated by the line 3—3 of FIG. 2.

I claim:

The ornamental design of a panel for a door, substantially as shown.
